UNITED STATES PATENT OFFICE

104,842

DESIGN FOR A BADGE OR SIMILAR ARTICLE

Juan F. Fleitas, Key West, Fla.

Application October 29, 1936, Serial No. 65,579

Term of patent 7 years

To all whom it may concern:

Be it known that I, Juan F. Fleitas, a citizen of the United States, residing at Key West, in the county of Monroe and State of Florida, have invented a new, original, and ornamental Design for a Badge, or Similar Article, of which the following is a specification, reference being had to the accompanying drawing, forming part thereof.

I claim:—

The ornamental design for a badge, or similar article as shown.

JUAN F. FLEITAS.
